UNITED STATES PATENT OFFICE.

FLOYD H. HUTCHINSON, OF HOVER, WASHINGTON.

TORPEDO-PLANTING DEVICE.

1,330,322.

Specification of Letters Patent. Patented Feb. 10, 1920.

Application filed July 24, 1919. Serial No. 313,094.

To all whom it may concern:

Be it known that I, FLOYD H. HUTCHINSON, a citizen of the United States of America, residing at Hover, in the county of Ben-ton and State of Washington, have invented 5 certain new and useful Improvements in Torpedo-Planting Devices, of which the following is a specification.

This invention relates to a torpedo planting device and it has for its object to provide a simple and efficient structure by means of which signaling torpedoes such as are commonly used on railroads may be firmly planted upon the rails without requiring 15 the stopping of the train from which the torpedo is delivered and without requiring the employee who places the torpedo, to leave the train.

Further objects and advantages of the invention will be set forth in the detailed 20 description which now follows:

In the accompanying drawings—

Figure 1 is a vertical, sectional view 25 through the lower portion of a torpedo planting device constructed in accordance with the invention with a torpedo held ready to be planted,

Fig. 2 is an edge view of a part of the structure shown in Fig. 1, and

Fig. 3 is a side elevation illustrating the 30 parts in the positions they occupy after the torpedo has been planted.

Like numerals designate corresponding 35 parts throughout the several figures of the drawings.

The improved torpedo planting device constituting the subject matter of the present invention comprises a handle of any desired length the lower portion of which 40 is indicated at 5. A pair of spaced plates 6 is secured to the handle by means of bolts or other fastening devices 7. Arms 8 are pivoted at 9 between the plates 6 and are adapted to be moved from the position illustrated in Fig. 1 to the position 45 illustrated in Fig. 3. Secured to the inner faces of the arms 8 are strips of metal 10 which at their lower ends are first curved outwardly and are then bent upon themselves and extended 50 inwardly to constitute opposed flaring portions 11. Their extremities are bent at 12 to engage over lips 13 of pockets 14 whereby the latter are held in place. A torpedo 15 having spring fingers 16 adapted to resiliently engage the ball portion or head of a rail is illustrated in Fig. 1 in the position

it occupies preparatory to being planted. At this time these spring fingers project into the pockets 14 and lie between the side walls 14' on said pockets and the action of these 60 fingers holds the arms 8 in closed position against the tension of a spring 17. The spring 17 consists of a strip of spring steel that is bent upon itself and rests within the recess formed in the lower end of the handle 65 5. A wedge block 18 together with a bolt 19 hold this spring in place and the wedge block spreads the same.

When it is desired to plant a torpedo, a brakeman upon a moving train may, by 70 leaning over the rear end of the train, thrust the torpedo planter downwardly and into engagement with the rail. The ball of the rail acting upon the flaring portions 11 with a wedging action forces the arms 8 away 75 from each other until the spring fingers 16 snap over the extremities 12 of the strips 10. Thereupon the spring 17 acts to throw the arms 8 to the position illustrated in Fig. 3 leaving the torpedo in engagement 80 with the rail, as indicated in Fig. 2.

The opening movement of the arms 8 is limited by the engagement of the tapered portion 8^a of the arms with the tapered portions 5^a of the handle and it is apparent 85 that when the arms are thus thrown to open position the device may readily be withdrawn by the brakeman without danger of its being caught by the rail.

While the elements shown and described 90 are well adapted to serve the purposes for which they are intended, it is to be understood that the invention is not limited to the precise construction set forth but that it includes within its purview whatever 95 changes fairly come within either the terms or the spirit of the appended claims.

Having described my invention what I claim is:

1. A device of the character described, 100 comprising a handle, a pair of members movably connected to said handle and adapted to be held together by the spring arms of a torpedo, and flaring members carried by the first named members and 105 adapted to engage with and be spread by the ball portion of a rail, as and for the purposes set forth.

2. A device of the character described, 110 comprising a handle, a pair of arms pivotally connected to said handle, pockets supported from said arms for receiving

the spring fingers of a torpedo and flaring surfaces below said pockets.

3. A structure as recited in claim 2 in combination with spring means normally tending to move the arms apart.

4. A structure as recited in claim 2 in combination with spring means normally tending to move the arms apart and means for limiting the opening movement of said arms.

5. A device of the character described, comprising a handle, a pair of plates secured to the lower end of said handle, a

pair of arms pivoted between said plates, a pair of strips secured to said arms and bent to form flaring portions, pockets held by said strips and a spring carried by the handle and normally tending to move the arms away from each other, as and for the purposes set forth.

In testimony whereof I affix my signature in the presence of two witnesses.

FLOYD H. HUTCHINSON.
